VACUUM CLEANER NOZZLE

Robert Brown, South Salem, N.Y., John Kowalewski, Riverside, Conn., Peter Medwed, Pound Ridge, N.Y., and John Moughty, Old Greenwich, Conn., assignors to Consolidated Foods Corporation, Old Greenwich, Conn.

Filed May 11, 1973, Ser. No. 359,234

Term of patent 14 years

Int. Cl. D15—05

U.S. Cl. D7—173

FIG. 1

FIG. 2

FIG. 3

FIG. 4

FIG. 5

FIG. 6

FIG. 7

FIG. 1 is a perspective view showing the top front and one end of a vacuum cleaner nozzle according to our new design;

FIG. 2 is a top view thereof;

FIG. 3 is a front view thereof;

FIG. 4 is a rear view thereof;

FIG. 5 is an end view thereof looking at the left end as shown in FIG. 3;

FIG. 6 is an end view thereof looking at the right end as shown in FIG. 3; and

FIG. 7 is a bottom view thereof.

We claim:

The ornamental design for a vacuum cleaner nozzle, as shown.
